COMB FINISHING APPARATUS AND
METHOD

Frank J. Clark, Leominster, Mass., assignor to
Du Pont Viscoloid Company, Wilmington, Del.,
a corporation of Delaware

Application December 8, 1930, Serial No. 500,766
Renewed June 26, 1934

10 Claims. (Cl. 144—26)

The principal objects of this invention are to provide a method and means for taking off the fins or webs produced on the teeth of molded combs and other objects; to provide means for automatically discharging the combs; and to provide an improved form of fin cutting punch for the above mentioned purposes.

Other objects and advantages of the invention will appear hereinafter.

10 Reference is to be had to the accompanying drawing, in which

Fig. 1 is a side view of a cutting punch constructed in accordance with this invention, showing the parts in a position in which the punch is about to descend to trim the teeth of the comb;

Fig. 2 is a front elevation of a part of a series of these punches for punching simultaneously between the several teeth of the comb;

Fig. 3 is a view similar to Fig. 1, showing the punch at the bottom of its stroke;

Fig. 4 is a sectional view on the line 4—4 of Fig. 2 showing the punch risen again with the blank supported by it, another blank discharged, and a new blank in position for trimming, and

Fig. 5 is a cross sectional view of a comb on enlarged scale, showing in dotted lines the action of one of these punches.

One way of producing combs of plastic material is to mold the comb blank from above and below by dies which in order to remove them necessarily have slanting sides. This produces a comb having teeth T with slanting sides S and a fin F or web at or near the center. These fins or webs extend along all the teeth of the comb from one end to the other and also at the back of the teeth. This invention is designed to provide for removing these fins or webs in a simple and practicable manner and is not confined to combs as it can be applied to other articles made in the same way.

The first four figures show the punches for trimming off these fins. Each punch consists of a flat body part 10, a slanting cutting edge 11, a horizontal surface 12 at the top of the cutting part of the punch, and a slanting surface 13 above that. Of course, the body of the punch is so constructed that it can be supported in the machine in a rigid manner. I have shown two rods 14 extending along the machine through holes in the several punches by which they are lined up, and they may be guided at the back along the vertical surface 15 as may be desired.

The surface 11 is sharpened to provide two opposite cutting edges. The combs B or other articles are mounted on a support 16 which is pro-

vided with means 20 for holding the comb blank against being pushed back, which may be made in any desired way. The teeth of the comb are supported by portions of this support 16 extending under them, and of course, the support has 5 passages down through it for the punches. These punches are strung on the rods 14 so as to be spaced apart exactly the same distance as the ultimate width of the comb teeth is intended to be. The width of each cutter is the same as the 10 width of the ultimate intended space between the comb teeth. In the spaces between the cutters are spacers 17 hung on this rod 14 like the cutters and constituting a part of the gang cutter. These spacers have curved front and bottom surfaces 18 15 or they might be slanting surfaces in the same plane as the surfaces 13. These spacers fill all the space between each two adjacent cutters and constitute the means for pushing the blanks of the combs outwardly by engaging the ends of the 20 teeth as the blanks rise in the manner to be described.

In operation the punch and comb blank being in the position shown in Fig. 1, the gang punch is brought down as shown by the arrow in Fig. 3, 25 cutting through the spaces between the teeth and removing their fins F and webs. The punches finally reach the position shown in full lines in Fig. 3, and then move upwardly again to the position shown in Fig. 4.

Now comparing Figs. 3 and 4, it will be seen that when the cutter moves down, the cutting blade between the surfaces 11 and 12 goes entirely below the comb blank. Now, when the gang of cutters is raised, the comb blank is free 35 to move. Although the cutter is of the same thickness throughout, when it moves back there is no weight on the comb, and the cutter will not pass through its own slots made in the comb. Consequently the cutter carries the comb up with 40 it, as shown in Fig. 4. After one or two combs are carried up in this way and then the cutter moves down and back, the edges 18 coming in contact with the backs of the combs will gradually force 45 them out horizontally, as indicated in dotted lines in Fig. 4. Each complete stroke down and up of the gang of cutters brings up a comb underneath the combs supported on the surfaces 12, and then these are forced out front where they can be removed by hand or carried away automatically.

This constitutes a very simple manner of removing the fins or webs, and also delivering the combs to convenient points. It is an important economy to provide means on the punches them- 50 55

5 selves, which does not have to be operated independently thereof, for dislodging the combs in the manner that has been described. The punches are of simple construction and easily set up. The bank of punches and the support for the comb blank may be mounted for operation in any suitable type of press having a means for carrying and moving the bank of punches.

10 Although I have illustrated and described only one form of the invention I am aware of the fact that changes can be made therein by any person skilled in the art without departing from the scope of the invention as expressed in the claims. Therefore I do not wish to be limited to the exact 15 form shown, but what I do claim is:—

1. The method of finishing comb blanks, which consists in punching off the fins left at or near the middle of the teeth of a pressed comb blank, raising the blanks on the punches and automatically discharging the blanks.

20 2. The method of finishing comb blanks, which consists in moving a gang of punches down between the teeth of a blank until they pass entirely through the blank, then raising the punches to carry the blank up with them and automatically discharge the blank from the punches.

25 3. A device for the purpose described, comprising a series of flat punches spaced apart a distance equal to the distance between the teeth of the comb and having cutting edges for punching out the fins on the sides of the teeth, said punches being connected together rigidly and spaced apart accurately and having a horizontal portion at the top adapted to lift each comb up above it as the punch goes down through the comb and comes back up to its original position.

30 4. A trimming device for toothed articles, comprising a series of punches, each punch having two opposite cutting edges arranged on a slant, said punches being adapted to be moved down between the teeth of the article taking off the fins or webs on the sides of the teeth, said punches having horizontal surfaces above the slanting cutting surfaces for raising each article as the punch 35 is raised after passing through the article on the punching operation.

40 5. A trimming device for toothed articles, comprising a series of punches, each punch having two opposite cutting edges arranged on a slant, said punches being adapted to be moved down between the teeth of the article taking off the fins or webs on the sides of the teeth, said punches having horizontal surfaces above the slanting cutting surfaces for raising each article as the 45 punch is raised after passing through the article on the cutting operation, and each punch also having a slanting surface at a higher level than the horizontal surface for forcing the article outwardly as the punch reciprocates.

6. As an article of manufacture, a punch for the purpose described, comprising a main body having parallel sides, a slanting cutting edge, a flat surface spaced from the cutting edge, and a slanting non-cutting surface beyond the flat surface, for the purpose described.

5 7. As an article of manufacture, a punch for the purpose described, comprising a main body having parallel sides, a cutting edge, a horizontal surface above the cutting edge, and a slanting 10 unsharpened surface above the horizontal surface.

8. As an article of manufacture, a gang cutter comprising a series of cutting punches each having an inclined cutting surface with a cutting 15 edge on each side and spacers between the cutting punches each having a surface extending upwardly and forwardly and extending throughout the spaces between two cutting punches for engaging the ends of the teeth of an article cut 20 by the punches and pushing them forward as these articles are raised in the gang cutter.

9. A trimming device for toothed articles comprising a series of vertically moving vertical punches, each punch having two opposite cutting 25 edges gradually extending upwardly toward the front of the cutter for cutting down between the teeth of the article to be trimmed or cut and each having a horizontal surface thereabove which, after being forced down through the article, will 30 upon its rising stroke, lift the article with it by engagement with the surfaces through which it has cut and spacers between said punches each having a surface which will be engaged by the ends of the teeth of the articles being punched 35 as said articles are raised in the cutter and will limit the rise of such articles and transmit the force used in raising them into a horizontal force to push them out of the cutter in a forward direction.

40 10. A trimming device for toothed articles comprising a series of vertically reciprocable punches, each punch having two opposite cutting edges on the lower side thereof, whereby when the punch is forced down between the teeth of a previously 45 formed toothed article the said edges will cut the fins or webs therefrom, each cutter having a horizontal surface of the same width above the cutting edges, whereby after the punch has cut down through an article and been raised again, 50 the horizontal surface will carry the article up with it and this action will be repeated on each movement of the trimming device, said trimming device also having a series of spacers between the punches, each having a surface which will engage the articles as they are thus forced up above 55 said horizontal surfaces and push them laterally out of the trimming device one at a time.

FRANK J. CLARK.
